UNITED STATES PATENT OFFICE.

MAI RAGLAND DOBBINS, OF ATLANTA, GEORGIA, ASSIGNOR OF ONE-HALF TO WILLIAM T. HUDSON, OF ATLANTA, GEORGIA.

DESIGN FOR A MAIL-BOX POST.

Application filed February 8, 1926. Serial No. 16,449. Term of patent 3½ years.

To all whom it may concern:

Be it known that I, MAI RAGLAND DOBBINS, a citizen of the United States, residing at Atlanta, in the county of Fulton and State of Georgia, have invented a new, original, and ornamental Design for a Mail-Box Post, of which the following is a specification.

Reference being had to the accompanying drawing forming a part thereof,—

The new and ornamental design for a mail box post, a typical form of which is shown in the accompanying drawings.

In testimony whereof I have hereunto set my hand.

MAI RAGLAND DOBBINS.
